Palm Of Wife

Nov 19, 1833

The inventor refers to in this Patent and Mfg
part of the same containing a description in the words
of the said John S. Wise, of his improvement
in the mode of tuning pianos and other strung mu-
sical instruments.

In all relations it may concern —
Be it known that I John S. Wise of the City of Bal-
timore in the State of Maryland have invented a new &
useful improvement in the mode of tuning pianos and
other strung musical instruments which I have called
Wise's Mechanical tuning hammer and which is
accurately described in the following words and figures
My improvement consists of a mechanical combina-
tion, founded upon the fact or principle that sound ap-
pearing on strung instruments varies with the degree of ten-
sion given to the strings being "tight" in musical lan-
guage as the tension is increased and "low" as it is de-
creased. Every string is capable of producing a
certain number of musical notes, and the same degree
of tension will produce the same note on strings of the
same size and length, or within so close an approxi-
mation as to render any difference imperceptible to the
ear. It is also a fact upon which my improvement
is founded, that the degree of tension to produce any given
note is capable of being measured and ascertained to a suf-
ficient degree of exactness. If therefore a person wish-
ing to tune a strung instrument should before
himself with the means of giving to a string the tension
necessary to produce a certain note he will be able to
tune the string to the required note even though he
should never have tuned a strung instrument
before, be utterly ignorant of music and therefore

1501
you should not have in ordinary practice "any comfort
needed". The mechanical combination on the grand
ly which I produce this result consists of two parts —
viz a peculiar arrangement of the fastening of the move-
able ends of the strings of the instrument & a mechan-
ical tuning lever, the construction of these two
parts is as follows, 1. the fastening of the moveable ends
of the strings, there may be made in various ways, but
all must comply with the condition that the tuning
pin shall move perfectly free, and as far as prac-
ticable, without any other friction than that which
the tension of the string may cause. In ordinary
stringed instruments, the tuning pin is made to
retain the string at the required tension by the fric-
tion of the pin in the tuning block, in a piano or
harps, or the same pin in the neck of a guitar or vi-
olin. In my improvement there must be as much fric-
tion if practicable, or as little as practicable, so that
the least perceptible tension shall be sufficient to move
the pin only retained by other than its own friction
in the substance in which it is fast, The mode which
I have adopted although there may be many others equal
by effect is to have screwed to the tuning block on a
piano, a metallic ledge, which is represented at figure
No 1. on the accompanying drawing, where a section
of it is given at the letter A.A. about one fourth of
an inch thick, and one and a half — wide
placed about one and a half inch from the tuning
block by a metal support B. which in its turn is
fixed to a base C.C. the ledge support and base being
all of the same piece of metal and secured to the tuning
block by the screw at D. The holes for the tuning pins are
in the ledge A.A. and occupy the same relative position

ordinary) and corresponding, with each handle, on the
lodge is a smaller one $\frac{1}{4}$ below in the base. The turning
pin L.D. is of the size of the hole in the base, say one fourth
of an inch in diameter, and has screwed upon it a fixed
nut of the shape T.T.I. the upper or movable part of
which T.I. fits so as to bear with the least possible pressure
upon the hole in the base. The mode in which this nut
is fastened to the turning pin is made necessary by the base
and base being inseparable. Above the base A.A. and
on the turning pin, is a movable thumb screw T.T.B. by
turning which the base is pressed or loosened between
the thumb screw and the shoulder T.I. of the fixed nut.
the turning pin secured in any required position —
the string H. is fastened to the turning pin near where
it enters into the base, at K. of the turning base —
the way to prep the strings on the blade of the turning
base, which is done upon the turning block, in the
ordinary mode of construction by making the strings
prep against small brad pins, place a small piece
of steel or wire for every two strings L. which I press
against them by a second passing through it, and down-
ing between the two strings into the base of the turning
base. This may be dispensed with though I think
it preferable to use it. 2. The turning however:
This consists of a steel pipe, see the figure B. in the ac-
companying drawing B' with a hole at bottom fitting the
head (to fig. 1.) of the turning pins and the upper ends
of which pipe passes into a cylindrical box B. and is
made to connect pt. B (fig. 2.) by means of a lever
(B.R. fig. 3) with the two ends of steel springs M.M.
(fig. 2.) the other ends of which are fastened to the top P.
 R. (fig. 3.) so that by turning the box B. the resistance
which the turning pins exert to the pipe B (fig. 2.) may

and the box. B. B. fig. 2. covers the opening A. A. and is so arranged as may be best suited to the time by means of small screws at (a. a. fig. 2.) and forming the top of the box in a dial plate. A figure marked with some initials to indicate, through the agency of the spring, the pressure applied at any moment, and the scale of which has been previously ascertained by experiment. The edge of the dial plate (m. m. m. fig. 2.) is notched so that it may be retained in any given position by a catch fixed on the box E. fig. 2. forming the well known contrivance of a ratchet and click. The ring C. C. fig. 2. is made fast to the box. The box with its contents is placed upon a frame of metal B. B. fig. 2. so made as to raise the box by small legs G. G. fig. 2. a proper distance from the ledge A. A. fig. 1. The pipe E. fig. 2. passes through this frame permitting the box to move on the frame around it as an axis.

The mode of applying, the mechanical tuning hammer and the measures of its operation is as follows. The pipe is put upon the tuning pin, when the frame will be found to rest on its legs on the ledge A. A. fig. 1 and the tuner turns the box B. fig. 2. to tighten the string to be tuned, first loosening the thumbscrew B. B. fig. 1. The tuning pin moves freely on the ledge, until the string begins to pull when the spring is contracted and the dial plate necessarily travels forwards. The tuner then continues to turn the box until the index points to the mark on the dial plate, which indicates the degree of tension necessary to produce the required note on the particular string. The catch then holds the dial plate from travelling backwards, while the tuner turns the thumbscrew and confines the tuning pin in the position to which he has brought it, thereby maintaining the proper degree of tension to produce the note required.

should the metal holder B fig. 1 break
it is most screwed down on the strings — — —
In addition to the ratchet and click of the dial plate
and key. I use an endless screw D. fig. 2 for the
purpose of making more minute divisions. This is fast-
ened to the frame at P.P. fig. 3, and works into a eye
projecting from the bottom of the key. It will be recollect
moving round the pipe through the frame. The
points on the dial plate indicating the tension for
all required notes, are previously ascertained by trials
and appropriate instructions for the application of the
instrument to the different strings accompanying it.
In connection with the mode of fastening the
moveable ends of the strings here before described,
and for the purpose of simplifying the operation of the
mechanical tuning hammer. I use a new method
of stringing the piano, by which one tuning pin
is made to answer for two strings, by which the num-
ber of tuning pins is reduced to one half and the time
required to tune the piano is shortened. Two adjoin-
ing strings as A.B. fig. 4, are passed over the same pin
of wire, the two ends of which are fastened to the adja-
cent hitch pins C.D. fig. 4. In the loop which is for-
med in the wire by this arrangement a pulley whose
diameter is equal to the proper distance between the two
strings when stretched is placed E. fig. 4, which pulley
has a strap and hook F. fig. 4, to which is fastened
the wire that goes round the tuning pin. The
motion of the tuning pin draws back the pulley, and
stretches the string on either side of it equally, and
where a sufficient tension is given the pin of iron
or steel G. fig. 4, is screwed down and confines the
strings. On making use of the mode of stringing a piano

and the tuning bridge is moved far enough back to make room for the pegs, and the screws which are at B. fig. 1, confine the strings across into a separate fixture for them. The above described mode of stringing two strings to one tuning pin may be used, or not at pleasure. The construction of the tuning of a piano or other stringed instrument may always be facilitated by applying the box to the tuning pin and bringing the index to the proper position on the dial plate.

The construction here described is particularly fitted for the piano and harp. A small modification would be necessary for the guitar and violin.

What I claim as new, and for which I ask an exclusive privilege is 1. The arrangement or mode by which the movable ends of the strings are fastened or tensioned, as well when there is a tuning pin to each string as when the piano is so stringed as to require only one tuning pin for two strings. 2. The mode of tuning a piano or stringed musical instrument without the assistance of the ear by measuring and ascertaining the degree of tension necessary to produce any required note on a given string or strings, and furnishing the tuner with the means of applying that degree of tension precisely and mechanically, and 3. The combination by which the end desired is effected.
